604,151, now Patent No. 2,104,709, dated Janu-
ary 4, 1938. Divided and this application
March 5, 1937, Serial No. 129,197

2 Claims. (Cl. 299—462)

This patent matures from a patent application carved from my parent patent application Serial No. 604,151, filed April 9, 1932, patented January 4, 1938, No. 2,104,709. It is thought that 5 a reader hereof will be helped to a quicker understanding of the invention claimed herein as compared to the invention claimed in the parent case, by the following remarks that are in the nature of a prologue.

10 The invention of the said parent patent application was described, for the purposes of illustration, as being used in a closed-circuit grinding system comprising a grinding mill, a primary classification stage, and a secondary classification 15 stage.

A quantity of one of the products of the secondary classification stage was described as having two advantageous uses. One use was by being supplied to the grinding mill, and the second 20 use was by being supplied to the classifier bath in the classification stage. It became apparent during the time that the said patent application was being prosecuted, that there was disclosed there- 25 in a multiplicity of inventions. The first invention related to improvements in closed-circuit grinding or in grinding-mill circuits; the second invention related to improvements in methods of classification claimed in my copending application Serial No. 74,833, filed April 17, 1936; and 30 the third to improvements in classifier apparatus.

The present case is drawn to the third feature, namely, improvements in classification apparatus, and resides in the provision of means whereby the density of the classifier bath is 35 increased.

In the parent case, from which there have been carved out two divisional cases drawn to the above-mentioned second and third inventions respectively, of which this case covers the 40 third, there is a disclosure of the desirability of supplying a grinding mill with solid material in colloidal form, that is, material whose particle size has a diameter that causes the material to act as a colloid; in other words, to have a tendency to remain in suspension.

Such colloidal material has a novel and unexpected effect in the grinding mill. It has also been found to have a novel and unexpected effect when supplied to the classifier bath or pool. 50 So this invention is directed to a classifier apparatus having provision for supplying to the pool or bath thereof colloidal material or material having its particles of colloidal size for the purpose of increasing the density of the classifier bath, by virtue of which greater selectivity of

classification may be obtained by classifiers of present-day general types, irrespective of whether or not they are used in a grinding-mill circuit. This feature of advantage will be found and described with more particularity in the latter part 5 of the following specification.

This finishes the prologue, so there now follows the main body of the specification, copied from parts of said parent patent application.

This invention revolves about the setting up 10 and maintaining in the grinding device, a condition of plasto-lubricity which is brought about in a simple manner by feeding to the grinding mill, slime having certain characteristics, the chief of which is that it shall contain as many as possible 15 of colloidal-like particles. In theory these particles should be of the diameter of a micron or less, but in practice I aim to use particles having a diameter up to and including that of a suspensoid which sometimes is called a suspen- 20 sion. An ideal concurrent condition would be to have the slime substantially free of particles between a micron and oversize, but this is not possible in commercial operating conditions, so I approach this condition as nearly as possible 25 under operating conditions. This slime may be added to the mill as a separate substance, such as bentonite. However, in tests with closed circuit grinding, it has been shown that in grinding practically every substance capable of such treat- 30 ment, the grinding operation automatically produces slime, some portion of which, contains the desired size of particles. So under all normal conditions, no extraneous material is likely to be needed to get the required slime conditions, 35 at least after they have been first built up within the grinding circuit.

But one feature of the required slime condition is that there be added to the mill, a minimum of 40 unfavorably sized particles or grains between those of a micron in size and those which are of the desired mesh for which grinding is being done. For example, suppose we are grinding to get a 48 mesh product. There will be in the mill solids ranging from molecular size to those 45 up to suspensoid size. Let us call that range A. Then there will be other solids falling in a range which will be called B including sizes from suspensoid to say —65 mesh. There will also be solids of +65 —48 mesh, which will be called 50 C. And those larger than 48 mesh, or oversize, will be called D. It is those in the range B that this invention teaches should NOT be recirculated to the mill, for they are already small enough so the mill should not be burdened with 55

them. It is the quantity thereof which should be kept down to a minimum. It is the grains in the range A which I refer to as the favorable fraction of slime that I want to have continually present in the mill. Those in the range C constitute the finished mill product, while those in the range D must be recirculated to the mill for further grinding.

This invention therefore, also contemplates the separating or selecting out from the mill discharge, solids in various size ranges whereby those in range C are removed from the circuit and are ready for some type of subsequent treatment; those in range B are removed from the circuit and join those in range C as finished product, while those in ranges D and a necessary portion of those in range A are recirculated through the mill along with the new mill feed. So a most important point of this invention lies in recirculating to the system, or through the mill, slime having colloidal types of solids within size limits up to a suspensoid as well as oversize, while eliminating as far as possible from the mill return all other fines or slime.

I have accompanied this specification with a drawing for illustrative purposes. In the drawing, Figure 1 shows diagrammatically the manner in which the mill discharge is subdivided and treated, Figure 2 shows diagrammatically how a balanced condition is set up in the secondary classifier Y.

In a simple application, the invention may be carried out in a grinding mill circuited with a classifier. The mill discharge is fed to a primary classifier. This classifier separates out the oversize which is returned to the mill and the overflow from the classifier contains the desired fines plus slime. This overflow is then exposed to further separation or selection such as by classification or hydroseparation where the desirable fines plus the fraction of slime unfavorable to grinding are discharged at the sand end of the classifier and the fraction of slime favorable to grinding is recovered from the slime end of the classifier.

This favorable fraction preferably is returned to the mill for recirculation therethrough. The discharge from the secondary classification or separation contains the other or unfavorable fraction of the slime plus the end product sands and some portion of the favorable fraction of slimes, the mixture of which form the finished product of the circuit. As will be shown later, my invention provides simple means for controlling a proportion of the favorable slimes in the system, which are eliminated from the system with the finished material, and of keeping the amount of slimes so eliminated equal to the amount of slimes produced in the mill.

But in practice, it is not as easy to do as might appear. Certain conditions must be caused to exist in the classifying stages in order to obtain the precise selectivity required.

Referring to Fig. 1, and to the flowsheet shown therein, the new mill feed enters the ball mill and so does the circulating load. The mill discharge is composed, as usual, of oversize, fines and slime. The discharge goes to a primary classification stage or classifier X. This classifier makes two separations. The oversize sands are separated and discharged by the classifier from whence they are returned to the mill as circulating load. The separated overflow from this classifier contains the fines plus the slime

produced by grinding in the mill and what slime is circulating in the system.

This overflow from the classifier X, composed of fines and slime, is then fed to a secondary classification or other separation stage such as a classifier Y. In this classifier, the two portions or fractions of slime are selectively separated, the unfavorable fraction of which with the finished fines are discharged and are ready for use. The favorable fraction of slime may preferably be overflowed from classifier Y into a compartment or reservoir Z from whence it goes to recirculation to the ball mill or classifier, or to both. The unfavorable fraction, composed of the larger sized slime solids are thus discarded or eliminated from the circuit and thus are precluded from getting back into the mill. They are ejected or rejected from the system or circuit by being mixed with the finished fines and exit with them.

The circulation through the mill of this favorable fraction of slime produces the various desirable conditions in the ball mill hereinbefore referred to and which I term plasto-lubricity. That is, the individual grains in the mill adhere to and coat the balls and yet the balls and the mass of sands are mobile and cascade freely independently of each other.

Referring now to the classifier X, greater selectivity is required than is ordinary. This can be accomplished in various ways. I propose now to make certain modifications of the classifier. One constitutes increasing the density of the classifier bath in order to refine the selectivity or efficiency of classification of the classifier. This increase of density of classifier bath may be done in any suitable manner, although my preferred plan is to return to the classifier bath some of the favorable fraction of slime. The favorable fraction of slime tends to have a constant density. In one ore treated, the density of the recirculated fraction of slime was maintained fairly constantly at 1.23, but of course this can be varied to meet the requirements of different ores or materials being ground or to meet different conditions in grinding the same material.

The reason for this increased density of classifier bath is to endeavor to preclude the passing to discharge of any undesirable larger particles or unfavorable fraction of slime. The discharge from this classifier is oversize which returns to the mill for regrinding, so if this discharge should include any appreciable quantity of the unfavorable fraction of slime or of critical sized fines the aim of this invention tends to be defeated, for one feature of the invention is the keeping out of the mill those larger sizes of slime solids which I have found to prevent efficient grinding.

The increased density of the classifier bath also serves as a determinant for the critical mesh or sized fines which are usually uncertain just which way to go—to discharge or to overflow. The increased density determines for them that they are to go to overflow and away from the discharge end of the classifier. So by increasing the density of the classifier bath I have found that improved selectivity of the classifier is obtained and it can be depended upon that most of the critical mesh sizes will be kept out of the oversize sand discharge.

I may also control the selectivity of this classifier by supplying to the classifier a certain volume of the favorable fraction of slime, and also by increasing the velocity of overflow over the end

weir. This increased volume of slime feed, and the increased volume of overflow causes a dispersion of the critical mesh sizes in the classifier which makes for cleaner classification. Thus I contend that in a classifier, I can improve the selectivity of classification by increasing the density of the classifying medium coupled with an increase of volume of fluid fed thereto, and an increase of velocity of overflow. In this particular instance, an increase of volume of fluid fed the classifier also produces increased velocity of overflow, but I can conceive of circumstances where other means than increased volume of fluid feed is necessary to increase the velocity of overflow. That is, I propose to improve classification or selectivity of classifier X by doing three things, namely, circulating slimy fluid to the classifier to increase the volume of fluid passing therethrough; increasing the velocity of overflow over the end weir which may also be a submerged weir; and increasing the density of the classifying medium. While increasing the density of the classifying medium, I may, by recirculating slime, increase the dilution of the classifier overflow, since the slime recirculated will normally have a higher dilution than the classifier overflow, as they form a selected portion of the overflow solids together with a major portion of the water and have a density lower than the primary classifier overflow. At the same time the ratio of slimes to water in the primary classifier overflow is maintained relatively the same if not increased.

The density, the volume of fluid fed, and the velocity of overflow must be carefully controlled for the particular material being treated so that the density will be high enough to cause the assured overflow of the critical sizes of fines but not high enough to carry oversize to overflow. But once the proper control is found for the material being treated, little attention need be given it further, for once set, the conditions of the bath remain fairly constant.

The overflow from classifier X, which is a mixture of fines and slime, then goes to further classification or selection. This further selection may be carried out in a number of ways but by way of illustration, let us assume this to take place in a secondary classifier Y. Here classification takes place but the operation of this classifier is controlled so that the finished fines are discharged and so are the unfavorable fraction of slime solids. That is, this secondary classifier Y, or any equivalent thereof which may be used, is depended upon to select out and to overflow the favorable fraction of the slime solids from the unfavorable fraction and the fines. The dependability of this separation or selection is important to the successful carrying out of this invention. So to be doubly sure that the selection of the favorable fraction of slime solids will be carefully accomplished, wash water is applied to the secondary classifier Y, as indicated on the flowsheet shown in Fig. 1. This sheet of wash water serves as a screen for holding back away from the discharge end, the favorable fraction of smaller slime solids. This assures their going out the classifier overflow and not becoming lost to the circuit by going out the discharge end along with the fines and the unfavorable larger slime solids. This classification and wash water also assure the unfavorable slime solids settling out whereby they are prevented from getting into the overflow and thus back into the circuit where they are so harmful. This wash water also has

the added function of restoring to the circuit, the water which passes from it through the secondary classifier discharge with the finished product.

In one mill circuit the finished product from the secondary classifier had a dilution of 50% or 1:1. Thus the end product is unusually dry. This precise amount of water has to be returned to the circuit but as the amount needed is fairly constant, it is a simple matter to set the new water being fed to the circuit, for it is merely correlated with the new mill feed on a 1:1 basis. If the finished product is to have a different dilution, the ratio of new water to new mill feed should be varied accordingly.

Reference has been made to the constant density of the recirculated slime and to the constant dilution of the sand discharge, both flowing from the secondary classification stage or classifier. This is accomplished by the setting up in that classifier of a condition of automatic balance. We have at the overflow end of the classifier a zone of greater density than in the zone at the discharge end. This is because of the wash water, which being applied substantially at the zone of emergence of the classifier blades, keeps the fines and slime washed back away from that zone, whereupon the zone of emergence of the blades becomes a zone of greater dilution. As the wash water washes back the slime and fines into the overflow end of the classifier, their concentration at that end sets up therein and thereat, a zone of increased density which is materially greater than the density of the zone of dilution or rake-blade emergence.

In Fig. 2 classifier Y is shown more or less diagrammatically in which 11 indicates the inclined bottom or deck of the classifier, 12 the overflow end, 13 the submerged weir, 14 the discharge end, and 15 the raking blades, or other mechanism. The submerged weir 13 divides the classifier tank into two hydraulically communicable compartments or sections, in one of which the raking blades 15 operate. The classifier overflows into the other compartment or section Z, in which the favorable fraction of slime flows and accumulates, and from which it is withdrawn through outlet pipe 16 controlled by a suitable valve 17. 18 indicates the zone of emergence of the raking blades 15 which is also the zone of dilution, while 19 is the zone of increased density. The wash water is added at 20. The normal horizontal liquid level for the classifier is indicated in full lines at 21, while the actual liquid level line assumed by the classifier bath under balanced conditions is indicated by the dotted line 22. As the density in the dense zone 19 is built up, it naturally takes more dilute liquid in the dilute zone 18 to balance it. In order to get enough of the dilute mixture in the zone 18 to balance the dense zone, the liquid level of the dilute zone rises and produces a superelevation. In effect, it is as if the classifier were a U-tube with the denser zone in one arm of the tube and the dilute zone in the other. Under these conditions, it can be visualized that the liquid in the dilute arm will be higher than the dense liquid in the other arm, if the liquid in the two arms is to be in balance. This is exactly what happens in this classifier, so the liquid level in the dilute zone 18 is automatically maintained higher than in the dense zone 19, for they thus balance each other. Under operating conditions, of course, with the incoming wash water there is a tendency for the liquid level in the dilute zone 18 to build up higher than is necessary to balance

the dense zone 19, and when this happens, the excess water passes out of the discharge end 14 of the classifier along with the raked product, because the classifier is so levelled that the discharge end intersects the plane of the balanced liquid level 22. But at the same time, this slight rising of the liquid level in the dilute zone reacts to raise somewhat the liquid level in the dense zone, and this slight rising thereof, causes an overflow over the weir 13 of enough slime to bring the liquid levels back into balance. Thus there goes on a constant building up of the level in the dilute zone which acts partly to discharge some of the wash water with the raked product, and partly to raise the liquid level in the dense zone whereby there is produced an overflow of the slime. However, one zone balances the other, so the two zones quickly, constantly, and automatically return to equilibrium. It is this automatically balancing condition within this classifier that causes the withdrawn slime to be of constant density. As has been stated, the slime withdrawn from this classifier constitutes the favorable fraction thereof which is circulated through the circuit, while the emerged discharge from this classifier constitutes the unfavorable fraction of larger slime solids and the fines, both of which form the finished product of the circuit. The selected favorable fraction of slime overflowing the weir of classifier Y is collected in some suitable container such as compartment Z from whence it is fed back to the mill or other desirable place in the circuit. The liquid level in the compartment Z is the same as that in the back end of the classifier adjacent to or abutting compartment Z and the weir 13 is submerged. This is necessary if, for any reason, an increased amount of liquid is withdrawn from compartment Z, the entire liquid level of the classifier drops momentarily and then all of the wash water is promptly retained until the liquid volume is restored and balance is again attained. In my preferred form of arrangement, some of the favorable fraction goes to the mill and some to the classifier X as has been explained above.

Operation.—In order to make the operation of this invention clear, let us assume a new closed circuit mill has been constructed and is ready to be started up. The operator will load up his mill and start it going along with the classifiers X and Y. However, his first object will be to build up in the circuit an ample supply of favorable fraction of slime. This could be done either by adding or introducing slime with appropriate characteristics to the circuit, or, by directing all of the water being added to the circuit to flow thereto through the wash water pipe 20.

As soon as an inspection tells the operator that there is enough favorable fraction of slime in the circuit to give him his desired mill efficiencies, and he observes that his classifier Y has reached a balanced condition, then he cuts down on the amount of wash water being fed to classifier Y and by-passes the remainder of the new water required by the circuit (to make up for the water losses going out with the raked end product) so that it is led to classifier X, and preferably mixed with the slime feed thereto. The regulation of the amount of wash water being fed to classifier Y is the one important adjustment in the whole system for otherwise all of the conditions appear to be automatically adjustable. He watches his

feed water to make sure it is just enough to keep the classifier Y in operating balance. If he does this, the density of the discharge product from classifier Y contains the fines plus the undesirable or unfavorable fraction of slime solids and its dilution is constant at whatever is wanted, such as 1:1. This also gives him the favorable fraction of slime withdrawable from the classifier containing a minimum of unfavorable sized slime or fines and also assures him of a constant density of the favorable fraction of slime. This favorable fraction of slime is circulated to the mill, to the classifier X, or to both, as may be found to give the best milling conditions wherein the grains stick to and coat the grinding media, and the grinding media and the mass being ground are freely mobile with respect to each other. In other words, to produce the conditions in the mill of what I have termed herein Plasto-lubricity.

He also checks the overflow from classifier X to make sure that conditions therein are correct. That is, to see that its bath is dense enough to assure proper selectivity thereof, as well as the volume of inflowing or infeeding slime thereto and also the velocity of overflow, for it is imperative that a maximum of critical mesh sizes and fines are kept in the overflow. If this classifier is not classifying to the degree required, he brings it to proper functioning usually by feeding a greater quantity of the favorable fraction of slime from the classifier Y overflow (or compartment Z) until conditions are right. If too much slime is being discharged with the raked oversize in classifier X, he will cut down on the quantity of favorable fraction of slime being fed to the classifier until the slime and fines are being properly overflowed by this classifier X. And that, along with any desirable variation in rake speed, is about all the operator needs to do for once the circuit is functioning well, it tends to continue to do so with very little attention. The circulating load seems to take care of itself and automatically adjusts itself to any variation in the ore being ground.

I claim:

1. Classification apparatus comprising a tank having a sloping bottom deck providing a bath space having a deep end, raking mechanism for conveying solids settled on said deck to emerged discharge, a feed supply of pulp to be treated, an outlet for suspended slimes from said deep end, a weir between the slimes outlet and the emerged discharge disposed to divide said bath space into two sections, an agitated and a quiescent one, in one of which operates said raking mechanism, the other one of which includes said deep end and said suspended slimes outlet, control means for said slimes outlet arranged and adapted to insure constant hydraulic communication of the liquid bodies in both said sections across said weir which is accordingly submerged.

2. Classification apparatus according to claim 1, with the addition of means for introducing controlled amounts of diluting water into the rake discharge section and substantially in the discharge zone thereof, thereby creating a zone of relative dilution at or near said discharge and a zone of relative density and viscosity at or near said slimes outlet.
